UNITED STATES PATENT OFFICE.

EDGAR BEVERLEY FENBY, OF LEAMINGTON SPA, ENGLAND.

MACHINE FOR USE IN THE MANUFACTURE OF LINEN COLLARS AND THE LIKE.

Application filed December 28, 1920. Serial No. 433,720.

To all whom it may concern:

Be it known that I, EDGAR BEVERLEY FENBY, residing at 28 Grove Street, Leamington Spa, in the county of Warwick, England, a subject of the King of Great Britain and Ireland, have invented certain new and useful Improvements Relating to Machines for Use in the Manufacture of Linen Collars and the like, of which the following is 10 a specification.

In the manufacture of fourfold linen collars, two strips of lining material and two strips of linen are cut to the configuration of the collar, and in the first stages of manu- 15 facture the edges of one strip of lining and one strip of linen are folded inwards together to form a hem, and whilst under the action of the folding tools are simultaneously heated and pressed to fix or set the 20 folds. Subsequently a pair of such parts are placed and sewn together with the linen portions outwards to complete the collar.

The present invention relates to the folding and pressing operations on linen collars 25 and the like, and has for its object to provide improved means for effecting these operations.

The invention comprises the construction 30 of a folder from a plurality of thin metal strips arranged side by side so that by relative sliding movements their operative ends can be caused to assume any desired configuration, thus enabling the one folder to be adapted to suit a collar or the like of 35 any shape.

The invention also comprises the construction 40 of the folder from relatively slidable sections so that all the edges of the folder can move inwards over the edges of the ma- 45 terial to be folded.

Further the invention comprises the combination with a heated pressure plate which operates in conjunction with the folder, of an expansible diaphragm or its equivalent 50 which under fluid pressure causes the desired pressure to be applied to the work.

Referring to the four accompanying sheets 55 of explanatory drawings:—

Figure 1 is a plan and Figure 2 a cross 60 section of a folding machine constructed in accordance with this invention; the end portion at the right hand side which is broken away on Figure 1 is similar to the left hand side which is shown.

Figures 3 and 4 are diagrammatic plans, 65 and Figures 5, 6 and 7 are diagrammatic

cross sections illustrating the stages in a folding operation effected by the machines shown in Figures 1 and 2.

Figure 8 is a plan illustrating the forma- 60 tion of the lock corners in the folded parts of a linen collar.

In carrying the invention into effect as shown, the folder is constructed from a number of relatively movable sections each 65 carrying a group of thin metal strips. The two main groups corresponding to the longitudinal edges of the article to be folded (which in the case illustrated is a linen collar) are represented by *a*, *b*, the end groups 70 by *c* and the corner groups by *d*. In addition, a special folding element *e* is provided at each of a pair of corners for use in the formation of what is known as the lock-corner. This will be referred to in detail 75 later. The groups of folder strips *a*, *b* are carried by slidable holders constructed in the form of clamps by which the strips can be secured. The bottom plate *f* of each of such clamps is continuous, but the upper 80 part is made from sections *g* each of which can be independently secured by a bolt *h* to the bottom plate. Each of these holders is carried at its ends by lugs *i* capable of 85 sliding in guides *j* on supports *k* secured on the base *l* of the machine. At its under side each holder is also carried on springs *m* located on pins *n* which freely enter foot pieces *o* capable of sliding on the base of the machine. These holders are pushed 90 apart by the interaction of spring actuated plungers *p* whose adjacent ends abut as shown in Figure 2. Movement of the holders toward each other is effected by compressed air cylinders *q* acting on brackets *r* 95 at the ends of the holders, the cylinders being movable on fixed hollow pistons *q'* carried on the above mentioned supports *k*. The brackets *r* are preferably hinged so that they can be swung out of the way to permit the holders to be lifted off the machine base, and to permit also removal of the said 100 cylinders for inspection or repair.

Each of the smaller groups of folder strips *c*, *d* is clamped to the underside of 105 and carried by a compressed air cylinder *s* movable on a fixed piston *t* carried by a support *u* on the base of the machine. The return movements of these cylinders are effected by springs *v*. The lock corner pieces 110 *e* are carried and actuated in like manner to the strips *c*, *d*, the cylinders, supports

and springs being indicated by the same reference letters *s*, *u*, and *v* respectively.

In conjunction with the folder is arranged a plate *w* (or shape) made to the configuration of the collar parts to be operated on, and carried by a counterbalanced arm *x* hinged on the machine base. An extension *y* at the underside of the arm serves to operate an air valve *z* as hereinafter described.

- 10 When setting up the machine, the plate *w* is brought down into contact with a table 2 over which the inner ends of the folder pieces can slide. The various clamping devices of the folding strips are released, and 15 the strips are individually pushed forward until their inner ends touch the edges of the plate *w*. To allow a little clearance between the ends of the strips and the plate after adjustment, all the cylinders are initially pushed forward slightly on their pistons. After the strips have been set and secured in their various clamping devices, the cylinders are returned to their proper initial positions. A small space is then left 25 between the inner ends of the strips and the plate, but the said ends of the strips accurately correspond with the configuration of the plate.

It will be apparent that to enable the 30 different groups to all move inwards simultaneously, the corner groups *d* must be capable of yielding. This is provided for by spacing the strips in these groups by short intermediate strips *d'* as shown in Figures 35 1 and 3. These groups can then contract laterally under the pressure of the adjacent rigid groups as shown in Figure 4.

The operation of folding will best be followed by reference to Figures 3 to 8. The 40 two similarly shaped parts, namely the facing and the lining, which require to be folded together along their edges in the manner indicated by Figure 8 are laid in a recess formed at the inner ends of the folder strips as shown in Figure 5, the parts to be folded being designated by 3. The plate *w* is then brought down and caused to carry the parts 3 between the ends of the folder strips into contact with the table 2. This 45 table is carried by springs 4 on a fixed plate 5 and the pressure exerted by the plate *w* is sufficient to depress the table 2 as shown in Figure 6. In this position the edges of the parts 3 are turned up as illustrated. 50 Subsequently compressed air is admitted to the various cylinders and the groups of folder strips are moved inwards over the plate *w* as shown in Figures 4 and 7. Pressure is now applied to the plate 2 and this is effected 55 by compressed air admitted by a connection 6 to a dilatable flat chamber 7 formed by a pair of thin metal plates, sealed around their edges. The said chamber is situated between the fixed plate 5 and an intermediate plate 60 8. Above the plate 8 and beneath the plate

2 is arranged any convenient electrically heated element 9, which heats the plate 2, so that the folded parts 3 are simultaneously heated and pressed, the pressure being transmitted to the plate 2 from the chamber 7 through the plate 8 and heater 9.

On releasing the air pressure in the chamber 7, and in the various cylinders which actuate the folder strips, the latter return under the action of the different 75 springs above mentioned, and the plate *w* under the action of the spring or weight operating on the arm *x* rises carrying the folded parts 3 with it. The parts 3 can then be stripped off the plate, and the operation 80 repeated on another pair of like parts.

For the production of lock corners use is made of the special folding elements *e*. The corners are square and are characterized by the turning of one fold over another as 85 shown in Figure 8. To produce these corners, the pieces *e* (whose flat operative ends are very thin) are caused to come into action first, in the operation shown in Figure 7. The springs *v* of the cylinders *s* which actuate the pieces *e* are rather weaker than the others, so that when the air pressure is admitted to the various cylinders the pieces *e* move in advance of the other folding strips. Starting with the edges of the parts 3 turned 90 up as in Figure 6, the pieces *e* move forward and turn down a portion of these edges at the corners. It will be noticed that the left hand piece *e* acts on a longitudinal edge of the material to be folded, whilst the right hand piece acts on one end. Subsequently when the other groups of folder strips move forward a part of the left hand group *e* moves over the left hand element *e* and the right hand end of the group *a* moves over 100 the right hand element *e*. A double fold is thus formed at each corner as shown in Figure 8. When the two opposite halves of the collar come to be sewn together, the adjacent lock-corners are first interengaged in 105 the usual manner.

For automatically controlling the flow of compressed air into and out of the various cylinders from a source of supply a valve 10 is used. Air from the source is admitted at 11 and initially the valve 10 is closed. At the upper end of the valve 10 is a head 12 contained in a chamber 13, air being admitted through a small orifice at the upper end of a longitudinal passage in the valve 10. Initially the pressure in the chamber 13 is the same as that of the source and the valve 10 occupies the lower position shown in Figure 2. When the arm *x* is swung down, an abutment 14 on the extension *y* opens the valve *z* thus releasing the pressure in the chamber 13 to atmosphere past the valve stem. Immediately the valve 10 then rises and first allows air to pass to the cylinders *q* and *s* through pipes connected to passages 115 120 125 130 135

15. When the folder strips approach or reach the inner limit of their movement a projection 16 on the plate *f* trips the abutment 14 and allows the valve *z* to reclose. 5 Pressure then immediately begins to accumulate in the chamber 13, but this proceeds relatively slowly owing to the smallness of the aperture in the upper end of the valve 10 and while this is proceeding the valve 10 continues to rise and admits air through the passage 17 to the dilatable chamber 7. When the pressure at the source is balanced by the pressure in the chamber 13 the valve descends and when it reaches its original 15 position it puts the passages 15 and 17 into communication with the exhaust outlet 18. The operation is repeated when the arm *x* is again moved down.

Among a variety of important advantages 20 resulting from this invention is that the inconvenience and expense associated with the usual folders necessitating a separate folder for each collar or like shape are avoided.

The invention is not limited to use in the 25 manufacture of linen collars as it may be applied to other analogous uses. Also the invention is not limited to the constructional details herein described as these may be varied to meet different requirement.

30 Having thus described my invention what I claim as new and desire to secure by Letters Patent is:—

1. In folding machines for use in the manufacture of collars and the like, a folding 35 element having a folding edge variable in shape from end to end, whereby an article may be folded to produce different configurations.

2. In folding machines for use in the manufacture of collars and the like, a plurality 40 of folding elements each having a folding edge variable in shape from end to end, whereby an article may be folded to produce different configurations.

45 3. In folding machines for use in the manufacture of collars and the like, a folding element including a series of relatively slid- 50 able plates arranged to form a folding edge variable in shape from end to end whereby an article may be folded to produce different configurations.

4. In folding machines for use in the manufacture of collars and the like, a folding element including relatively slid- 55 able groups of thin metal strips arranged to form a folding edge variable in shape from end to end, whereby an article may be folded to produce different configurations.

5. In folding machines for use in the manufacture of collars and the like, a folder consisting of relatively slidable groups of thin metal strips, the strips in all the groups being relatively adjustable to form folding edges variable in shape from end to end, the strips of one of said groups being laterally flexible, so that all the groups can remain in contact during their movements toward and away from each other. 60

6. In folding machines for use in the manufacture of linen collars and the like, 70 the combination comprising relatively slid- 75 able groups of thin metal folder strips forming folding edges variable in shape from end to end and adapted to fold the edges of the articles to be operated on, and supplemen- 80 tary folder elements adapted to operate in conjunction with said strips for producing double corner folds.

7. In folding machines for use in the manufacture of linen collars and the like, the 80 combination comprising groups of relatively adjustable thin metal folder strips, 85 holders for the said strips, fluid pressure cylinders for producing movements of the holders in one direction, springs for return- 90 ing the holders, a heated pressure plate over which the folder strips slide, a fluid pressure diaphragm acting on the said plate for pro- 95 ducing pressure between the pressure plate and the folder strips, a hinged arm, a shaped plate carried on the arm, the shaped plate being adapted to co-operate with the folder strips and pressure plate, a valve automatically admitting and releasing the pressure fluid to and from the said cylinders and dia- 100 phragm, means on the hinged arm for controlling the said valve, and means on one of the holders for putting the said valve controlling means out of action, substantially as described. 100

8. In a folding machine for use in the manufacture of linen collars and the like, a folder consisting in part of a folder element carrying member, a folder element actuated by said member and including a series of thin relatively slidable plates arranged side by side to form a folding edge variable in shape from end to end, each of said plates being independently adjustable in the direction of movement of the carrying member 105 for the production of different configurations. 110

In testimony whereof I have signed my name to this specification.

EDGAR BEVERLEY FENBY.
